JOEL A. OTIS AND THOMAS BARBER, OF WATERTOWN, NEW YORK.

Letters Patent No. 82,866, dated October 6, 1868.

IMPROVEMENT IN APPARATUS FOR TREATING MILK.

The Schedule referred to in these Letters Patent and making part of the same.

TO ALL WHOM IT MAY CONCERN:

Be it known that we, JOEL A. OTIS and THOMAS BARBER, of Watertown, in the county of Jefferson, and State of New York, have invented a new and improved Apparatus for Treating Milk; and we do hereby declare that the following is a full, clear, and exact description of the construction and operation of the same, reference being had to the annexed drawings, making a part of this specification, in which—

Figure 1 is a vertical cross-section.

Figure 2 is a top view.

Figure 3 is a side elevation.

This invention is a simple and cheap device for warming milk in the process of manufacturing cheese, and consists in a furnace, boiler, and milk-tank, so constructed, arranged, and operating, that the heat is applied uniformly at all parts of the tank where it is required, and in such a manner as to utilize all the heat, and warm the milk rapidly, without scorching or injuring it in any degree.

In the drawings, A represents a furnace, consisting of a simple inverted arch, a , of any suitable material, having a door at its front end, and a flat rectangular opening, c , at the upper edge of its rear or inner end. Around this inverted arch is a jacket, or surrounding arch, a' , also inverted in shape, like the former, and having its walls separated from the inner walls a by a narrow space, which is filled with water from above. The upper side of the furnace A is closed water-tight, the upper side of the enclosing-jacket a' is open, and connected with a flat rectangular boiler, B, of the form and relative dimensions seen in figs. 1 and 2, so that when such boiler is filled with water, the water covers the top of the furnace, and flows down between the walls a a' , as shown by the red lines of fig. 1. The flat flue C, starting from the upper and inner edge of the furnace at the opening c , passes around the boiler in a horizontal direction, as seen in fig. 2, terminating finally in a smoke-pipe, D, its position in the boiler being such that when the latter is filled with water, the flue is submerged, as shown in section in fig. 1.

In connection with this apparatus, we use a milk-tank, E, which fits into the rectangular boiler, as seen in fig. 1, its bottom resting in the water, above the flue C, and receiving the heat communicated therefrom. By making the flue flat and wide, as shown, it occupies less vertical space than if it were made round, and thereby saves material, besides radiating more heat. By extending it around the edge of the boiler, its radiating surface is increased, and the heat is conducted directly to every part of the boiler, and communicated to the water therein in a uniform and equable manner, so that, the water being uniformly heated, it in turn uniformly applies the heat to the milk, preventing the undue heating of any part of the latter.

The whole device is exceedingly simple, cheap, and convenient of operation, besides accomplishing the results above described quicker and in a better manner than by any apparatus hitherto in use for the purpose.

We do not claim, as our invention, a furnace surrounded with water, the water-space and the furnace being connected by pipes with the water-space under and around the milk-pan, for we are aware that such device is old, being shown in the patents of H. A. Roe and others. Our apparatus is more neatly and cheaply constructed than such devices as Roe's, the boiler, furnace, and flues being arranged much more compactly, and the whole costing but a trifle, as compared with the old devices. In our apparatus, it will be observed, the boiler and furnace compose but a single vessel, while the entire heat of the fire is radiated from the long convoluted pipe, C, in its course through the boiler. The compact furnace and boiler thus made in the form of a single vessel, and the convoluted pipe C, when constructed and arranged together as described, constitute the most important features of our invention. Without these parts, arranged as described, we lay no claim to novelty in its construction, but with them we have demonstrated, by a long course of practical experiment, that the apparatus is superior to all others heretofore brought into use for a similar purpose.

Having thus described our invention, what we claim as new, and desire to secure by Letters Patent, is—

The arrangement of the double-walled furnace A, with the boiler B and flues C C, when the furnace is made a part or extension of the boiler, and the flues are convoluted or bent back and forth, as shown, all the said parts being constructed, combined, and arranged in the manner described.

JOEL A. OTIS.
THOMAS BARBER.
